United States Patent Office

Des. 218,750

Patented Sept. 22, 1970

218,750

DATA PROCESSING CONSOLE

Clarence D. Zierhut, Granada Hills, Calif., assignor to
Data Instrument Company, a corporation of California

Filed July 9, 1969, Ser. No. 18,124

Term of patent 14 years

Int. Cl. D14—02

U.S. Cl. D26—5

FIG. 1.

FIG. 2.

FIG. 3.

FIG. 1 is a perspective view taken from the front and right side of a data processing console embodying my new design;

FIG. 2 is an elevational view taken from the left side thereof; and,

FIG. 3 is a rear elevational view thereof.

The broken line representation of the typewriter in FIGS. 1 and 3 is for purposes of illustration only.

I claim:

The ornamental design for a data processing console, substantially as illustrated and described.
